ATTY.

UNITED STATES PATENT OFFICE.

ARTHUR T. CROCKER, OF SCHENECTADY, NEW YORK, ASSIGNOR TO GENERAL ELECTRIC COMPANY, A CORPORATION OF NEW YORK.

CONTROL APPARATUS.

No. 872,990.

Specification of Letters Patent.

Patented Dec. 3, 1907.

Original application filed January 9, 1905, Serial No. 240,143. Divided and this application filed March 21, 1907. Serial No. 363,585.

To all whom it may concern:

Be it known that I, ARTHUR T. CROCKER, a citizen of the United States, residing at Schenectady, county of Schenectady, State 5 of New York, have invented certain new and useful Improvements in Control Apparatus, of which the following is a specification.

This application is a division of my pending application Serial No. 240,143, filed Jan. 10 9, 1905, for improvements in control apparatus, in which the present invention is fully described and illustrated.

My invention relates to control apparatus for electric motors and particularly to the 15 type of control apparatus set forth for example in the patent to Frank E. Case, No. 801,214, dated Oct. 10, 1905, for system of motor control.

One of the objects of the present invention 20 is to provide an improved mechanism for operating the emergency air-brake valve and the emergency circuit-breaker when the controller handle is released by the motorman.

Other objects of my invention will appear 25 from the following description which, when taken in connection with the drawings, discloses one embodiment of my invention.

In the accompanying drawings in which the same parts are referred to by the same 30 reference characters throughout all the figures, Figure 1 is a side elevation partly in section with a portion of the casing removed of a portion of a controller constructed in accordance with my invention; Fig. 2 is a detail of the upper portion of the controller 35 parts of which are removed in order to show the mechanism directly associated with the emergency air-brake valve; Fig. 3 is a section taken approximately on the line 3—3 of Fig. 1; and Fig. 4 is an elevation on the line 4—4 of Fig. 2 looking in the direction of the arrows.

A represents a portion of the controller casing within which are supported the controller parts. B is the controller cylinder. C indicates the reversing switch and D the controller handle. These parts may be of any usual or desired construction. The controller handle D is connected to and directly 50 operates the shaft 1 which extends through the top of the controller casing and is supported at its lower end within the boss 2 adjacent the upper end of the controller cylinder. This shaft 1, through certain flexible 55 connections and gears, is connected to the

controller cylinder B and by the rotation of this shaft 1 the desired rotation of the cylinder B is effected. The construction and operation of the parts intermediate the shaft 1 and the cylinder B are fully set forth in my 60 co-pending application Serial No. 240,143 heretofore referred to and as these devices form no part of the present invention, the description of them will not be repeated.

The emergency air-brake apparatus and the emergency circuit-breaker in the controller illustrated are located near the top of the casing. The usual emergency valve shown at E has projecting from its casing the valve stem 5. A dog 6 is pivotally secured at 7 to 65 a bracket 8 attached to the back of the controller casing. The valve stem 5 lies directly within the plane of movement of the dog 6 and is adapted to be engaged by it. When the reverser is in its "off" position the dog 6 70 is prevented from forcing the valve stem 5 inwardly by means of the rod 9 which is provided at one end with a notch 10, one wall of which engages with the upper end of the dog 6. The rod 9 is connected at its other end to 75 one arm of a bell-crank lever 11 mounted on a stud 12. The other arm of this bell-crank lever is connected by a link 13 with the collar 14 secured to the reverser shaft 15. When the reverser shaft is moved in either direction 80 in order to give forward or reverse motor connections, the bell-crank lever 11 is oscillated in a direction to move the rod 9 to the right, thereby releasing the dog 6 from engagement with the wall of the groove or 85 notch 10. A bar or shoe 18 is slidably mounted adjacent the dog 6 and is provided with a lug 19 which engages with a shoulder 20 on the dog 6 when the shoe 18 is moved 90 upwardly, thereby causing the dog 6 to force 95 the valve stem 5 inwardly and causing the brake to be applied. A convenient way for mounting the shoe 18 consists in passing rivets or bolts 21 through slots 22 in the shoe 18, the rivets or bolts 21 being secured in the 100 bracket 8. The shoe 18 is actuated by sliding cam 23 keyed to the shaft 1. This cam has a flange 24 which in all angular positions of the shaft 1 is beneath the projecting shoulder 26 of the shoe 18. The cam 23 is 105 normally held in its raised position by means of a spring 27 which engages at its upper end with the cam 23 and at its lower end with a collar 28 secured to the shaft 1. When the motorman places his hand on the controller 110

handle he depresses the button 30 and thereby through the pin 31 and the levers 32 and 33 depresses the sliding key 34 which bears at its lower end upon the cam 23, thus pressing this cam downward against the action of the spring 27. This movement of the cam 23 brings the cam flange 24 into alinement with a roller 36 carried upon the end of the arm 37 of the emergency circuit breaker 10 which is mounted for rotation on a short shaft 38. This circuit-breaker may be of any known or approved form and as shown comprises two contact fingers 39 which engage with the fixed contacts 40. When the 15 handle of the controller is turned, the cam flange 24 engages with the roller 36, thereby rotating the circuit-breaker and bringing the contact fingers 39 into engagement with the fixed contacts 40. If now, while the controller handle is in one of its running positions, the button 30 is released, the cam 23 flies upward under the pressure of the spring 27 and the cam flange 24 strikes the shoulder 26 on the shoe 18, thereby raising the shoe 25 and causing the lug 19 to engage the dog 6 and force the latter against the valve stem 5. At the same time the flange 24 passes above the roller 36 and allows the spring 42 to throw the contact fingers 39 outwardly from 30 the fixed contacts 40 thereby breaking the circuit at these points. This latter operation brings the roller 36 beneath the cam flange 24 thereby preventing the cam from being moved downwardly to release the 35 brakes until the controller handle is returned to the off position when, as shown in Fig. 3, the end of the cam flange 24 just clears the roller 36. If, therefore, while the reverser is in one of its running positions and 40 the controller handle is in a running position, the button 30 is released, the circuit is opened and the brakes are at once applied, and the controller circuit cannot be restored or the brakes released until the controller 45 handle is returned to its off position. In the off position of the controller handle when the reverser is in one of its running positions the brakes may be released and applied at will by depressing or releasing the button 30.

50 Although I have described the present invention as embodied in a certain form of controller, I wish it distinctly understood that I do not desire to limit my invention to any particular form of controller as it is obvious 55 that it may be applied to many types.

What I claim as new and desire to secure by Letters Patent of the United States, is,—

1. In a controller, an emergency air-brake valve, a circuit-breaker, a controller shaft 60 and a cam slidably mounted thereon, mechanism associated with the controller handle for moving said cam into operative relation to the circuit-breaker, and means operative upon release of the controller handle to move 65 said cam out of operative engagement with

the circuit-breaker and into operative engagement with said emergency valve.

2. In combination, a controlling handle, a shaft operatively connected to said handle, a brake-controlling device, a member slidably mounted on said shaft and arranged to coöperate with said brake-controlling device to cause application of the brakes, means including mechanism associated with the said handle for controlling said member, means for moving it into its brake-applying position upon release of the said handle, and means operative to automatically lock said member in said brake-applying position.

3. In combination, a controller shaft and handle, a brake-controlling device, a member slidably mounted on the controller shaft and arranged to coöperate with said brake-controlling device to cause the application of the brakes, means including mechanism associated with the controller handle for controlling said member, means for moving it into its brake-applying position upon release of the controller handle, and means operative to automatically lock said member in its brake-applying position in the running positions of the controller.

4. In combination, a controller shaft and handle, a brake-controlling device, a member slidably mounted on the controller shaft 95 and arranged to coöperate with said brake-controlling device to cause the application of the brakes, means including mechanism associated with the controller handle for controlling said member, means for moving it into its 100 brake-applying position upon release of the controller handle, means operative to automatically lock said member in its brake-applying position, a reversing switch, and means controlled by the reversing switch 105 for locking said member out of its brake-applying position.

5. In combination, a controller shaft and handle, a brake-controlling device, a circuit breaker, a cam slidably mounted upon the 110 controller shaft, mechanism associated with the controller handle for moving said cam into operative relation to the circuit-breaker so that the cam closes the circuit-breaker when the handle is rotated, and means 115 operative upon release of the controller handle to move said cam out of operative relation to the circuit-breaker and into brake-applying relation to the brake-controlling device, the parts being constructed and arranged so that the circuit-breaker is adapted to lock the cam in its brake-applying position if the controller handle is released while in a running position.

6. In combination, a controller shaft and handle, a brake-controlling device, a circuit-breaker, a cam slidably mounted on the controller shaft, mechanism associated with the controller handle for moving said cam into operative relation to the circuit-breaker so 130

- that the cam closes the circuit-breaker when the handle is rotated, means operative upon release of the controller handle to move said cam out of operative relation to the circuit-breaker and into brake-applying relation to said brake-controlling device, and means for opening said circuit-breaker and locking said cam in its brake-applying position when the cam is moved out of operative relation to the circuit-breaker.
7. In combination, a controller shaft and handle, a brake-controlling device, a circuit-breaker, a cam slidably mounted on the controller shaft, mechanism associated with the controller handle for moving said cam into operative relation to the circuit-breaker so that the cam closes the circuit-breaker when the handle is rotated, means operative upon release of the controller handle to move said cam out of operative relation to the circuit-breaker and into brake-applying relation to the brake-controlling device, means for opening said circuit-breaker when the cam is moved out of operative relation thereto, and a projection on said circuit-breaker adapted to engage with said cam to lock it in its brake-applying position if the controller handle is released while in a running position.
8. The shaft of a controller, a cam operatively connected thereto, a circuit breaker, a controlling means therefor operated from said cam, and an operating device having two motions, one motion adapted to rotate the controller cylinder, the other motion adapted to actuate said cam to place it into position to control the circuit breaker.
9. The shaft of a controller, a cam operatively connected thereto, a circuit breaker, a controlling means therefor operated from said cam, an operating device having two motions,
- one motion adapted to rotate the controller cylinder, the other motion adapted to actuate said cam to place it into position to control the circuit breaker, and means to prevent such shifting except from normal position.
10. The shaft of a controller, a cam operatively connected thereto, a circuit breaker, a controlling means therefor operated from said cam, and an operating device having two motions, one motion adapted to rotate the controller cylinder, the other motion adapted to actuate said cam to place it into position to control the circuit breaker, in combination with means to automatically break said circuit upon release of controller handle.
11. The shaft of a controller, a cam operatively connected thereto, a circuit breaker, a controlling means therefor operated from said cam, and an operating device having two motions, one motion adapted to rotate the controller cylinder, the other motion adapted to actuate said cam to place it into position to control the circuit breaker, in combination with means to prevent such shifting except from normal position and means to automatically break said circuit upon release of controller handle.
12. A device of the kind specified, comprising a rotating controller arm, an operating handle carried thereby, a controller shaft, a notched cam slidably thereon, a circuit breaker, and an operating arm therefor controlled by said cam when said operating handle is actuated.

In witness whereof, I have hereunto set my hand this 20th day of March, 1907.

ARTHUR T. CROCKER.
